UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,909, dated October 25, 1892.

Application filed September 29, 1892. Serial No. 447,330. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of my design consists of an arrangement of ornamental scrolls connected to form an ornamental panel, with a vase-shaped ornament filled with flowers inclosed within the ornamental panel, as represented in the accompanying drawing. A 15 small festoon of flowers and leaves hangs from the ornamental scrolls beneath the vase of flowers, and a small spray of flowers and leaves connects with the scrolls on each side of the vase of flowers and forms part of my ²⁰ design.

The design is printed in any desired color or bronze on tinted paper of any desired color.

What I claim is—

The design for wall-paper herein shown and ²⁵ described.

Witness my hand this 24th day of September, 1892.

CHARLES BOOZE.
